UNITED STATES PATENT OFFICE.

GEORGE ALFRED KIMBER, OF CHICAGO, ILLINOIS.

GRINDER.

No. 836,813.

Specification of Letters Patent.

Patented Nov. 27, 1906.

Application filed December 18, 1905. Serial No. 292,174.

To all whom it may concern:

Be it known that I, GEORGE ALFRED KIMBER, a citizen of the United States, and a resident of the city of Chicago, in the county 5 of Cook and State of Illinois, have invented certain new and useful Improvements in Grinders; and I do hereby declare that the following is a full, clear, and exact description of the same, reference being had to the accompanying drawings, and to the letters of reference marked thereon, which form a part of this specification.

This invention relates to improvements in grinding-machines, and more particularly to 15 a grinding-machine adapted for use in dressing abrasive wheels such as those employed in glass-cutting. Heretofore the dressing of glass-cutters' wheels has been performed entirely by hand, and in consequence, owing to 20 slight variations of hardness of stone or inequalities of other kinds, the stone soon becomes untrue and is therefore worthless. In 25 grinding said stones it is necessary to provide a central sharp cutting edge on the stone, perfectly true and having an unvarying angular edge, for any variation in the edge of the glass-cutters' stone is certain to injure the glass, even chipping it.

With this in view the object of the invention 30 is to provide a grinding-machine adapted to dress glass-cutters' and like stones with absolute precision, thereby securing uniformity of edge and adapted to be operated by one not thoroughly skilled.

The invention also has for its object the 35 construction of a grinding-machine having maximum flexibility of adjustment of the grinder and wherein the grinding operation may be performed at any desired angle with 40 the plane of rotation of the disk or cutter's wheel operated upon.

The invention consists in the matters hereinafter described, and more fully pointed out and defined in the appended claims.

In the drawings, Figure 1 is a side elevation 45 of a device embodying my invention, showing the glass-cutters' stone in position to be operated upon. Fig. 2 is a top plan view of the same. Fig. 3 is a rear elevation 50 of the grinder. Fig. 4 is a vertical section thereof. Fig. 5 is an enlarged longitudinal

section of one of the bearings for the arbor of the grinder.

As shown in said drawings, A indicates any suitable arbor suitably journaled to rotate 55 the glass-cutters' stone a with precision and at a high rate of speed.

B indicates a bottom clamping member adapted to be rigidly, though adjustably, secured to the bed-plate or ways of the machine or lathe upon which the grinding operation is to be performed by means of a clamping-bolt b. Said clamp is provided at its outer end with a tubular upwardly-extending cylindric boss b'; which is bored to afford a 65 cylindric vertical socket in which is secured the cylindrical end b² of a slide-rest B', which, as shown, extends horizontally and is provided in its top with dovetailed ribs b³, as shown in Figs. 1 and 3, and with which is 70 slidably engaged a slide D, provided, as shown, with a dovetailed seat in its under face complementary with the width and adapted to engage the dovetailed ribs on the slide-rest B'. As shown also, said slide is provided at its outer end with a downwardly-turned flange d, slotted upwardly from the bottom, as shown in Figs. 3 and 4, and in which is journaled the end of a screw-shaft d', the inner threaded end of which engages 75 in a complementary-threaded bore d² in the slide-rest B'. As shown, said screw-shaft is provided at its outer end with an angular head adapted to be engaged by a suitable crank or wrench d³ and whereby rotation of 80 said shaft acts to move the slide longitudinally of the rest. Located centrally on said slide D and extending vertically upward therefrom is an integral cylindric boss d⁴, corresponding with the cylindric boss or stud- 85 shaft b². Said cylindric boss fits closely in a cylindric socket e in a slide-rest E, corresponding with the slide-rest B', and likewise is provided at its top with dovetailed ribs e', extending longitudinally thereof and fitted into 90 a complementary dovetailed groove or seat in a slide E', corresponding with the slide D, and which is provided with a downturned flange e² at one end thereof. Rotatably engaged 95 therein is a screw-shaft e³, the threaded end 100 of which is engaged in a complementary-threaded socket e⁴, as before described, and

the outer end of which, e^5 , is rectangular to be engaged by a wrench or suitable crank. The top of said slide E' is shown as flat, and rigidly supported and bolted thereon is a stand-
 5 ard F, having upwardly-directed arms f, the upper ends of which, as shown, extend obliquely with and at an angle of approximately forty-five degrees with the longitudinal axis of the slide E'. Journaled in said arms is the
 10 grinding-arbor G. As shown, said arbor is secured axially in the upwardly-directed end of said arms, in which is provided an oval babbitt-chamber g, and bearing-sleeves g' are secured in the shaft or arbor, and the
 15 bearings are then babbitted, thus insuring perfect alinement. As shown, a belt wheel or pulley G' fits closely between the bearings for said arbor in said upturned arms f and is rigidly secured on said shaft by means of one
 20 or more set-screws and acts to hold the shaft from movement longitudinally in its bearings, and, as shown, at the outer end of said arbor is secured complementary collars g³ and g⁴, between which and secured upon the ar-
 25 bor by means of the nut g⁵ is the grinding or abrasive wheel H. Said arbor, as shown, is shaped at its opposite end to be engaged by a wrench or other tool. Said slide-rests and the slides are held at a definite angle with and
 30 are adjustable relative to each other by means of set-screws b⁵ and d⁵, which are seated in the bosses b' and e, respectively, and which engage the cylindric studs or shafts b² and d⁴ in suitable grooves therein and not
 35 only hold the parts from lifting, but as well rigidly engage the same in the proper angular adjustment to dress the glass-cutter's stone a at the desired angle.

The operation is as follows: The grinder-
 40 stone having been secured upon the arbor as desired and the operator having assured himself that the arbor and stone revolve accurately, the slides are adjusted upon their rests to insure a suitable angle at the edge of
 45 the cutting-stone H, as shown in Fig. 2. The arbor G is of course driven from any suitable source of power by means of a belt trained around the pulley G' to rotate the abrasive wheel H oppositely from the direction of ro-
 50 tation of the glass-cutter's wheel, and the grinding-wheel is rotated at a high rate of speed relatively to the cutting-wheel's speed. The slide D and the slide E are each adjusted to the desired angle—as, for instance, at ap-
 55 proximately a right angle with each other, or, in other words, each forty-five degrees with the plane of rotation of the wheel a and on opposite sides of the cutting-wheel—and the angular edge of the abrasive wheel
 60 H is adjusted against the wheel to be shaped, as shown in Fig. 2, by rotation of the crank e, thus cutting away the stone a at the angle shown in Figs. 1 and 2 or at any desired angle or to afford any desired peripheral con-

formation, dependent upon the angle at 65 which the slide E' is adjusted relatively of the plane of rotation of the wheel a. Having completed the cut on one side of the stone, the grinding-wheel is retracted by means of a crank and adjusted with the opposite cutting 70 edge thereof at the cutting edge of the wheel and by means of the crank d³ is moved inwardly, thus cutting the opposite face of the stone. In this manner the sides of the stone are cut alternately, and, owing to the pre-
 75 cision, the speed, and the accurate adjustment of the abrasive stone H relatively to the cutting-wheel, said cutting wheel or stone is shaped with the utmost precision to afford the desired cutting edge and refitted for the 80 work of the glass-cutter. It is of course immaterial that the glass-cutter's stone sharpened in this manner may vary in hardness at spots in its periphery, for the reason that, owing to the mechanical precision, the stone 85 will be accurately ground nevertheless.

While I have shown very simple forms of slide-rests and slides and a simple form of arbor secured thereon, it is obvious that details of construction and arrangement may 90 be varied, and I therefore do not purpose limiting this application for patent otherwise than necessitated by the prior art.

I claim as my invention—

1. The combination with two slide-rests 95 adapted to be arranged at equal angles relatively a common plane of a wheel rotating in said plane, a grinding-wheel carried on one of said slide-rests and movable by either or both of said slide-rests to dress the periphery 100 of the wheel.

2. In a machine of the class described the combination with a rotative arbor of a cutting-wheel secured thereon, a slide-rest adjustably supported on the frame for said arbor and adapted for adjustment at an angle for said wheel and a second slide-rest supporting the same and adjustable thereto and at an angle therewith.

3. In a device of the class described the combination with two slide-rests each pivotally supported and one mounted upon the other and adapted to be adjusted at angles one with the other, of an arbor mounted on the uppermost of said rests and at an oblique 115 angle with the longitudinal axis thereof and a grinding-wheel carried on said arbor at one end thereof.

4. In a machine of the class described a frame, a slide-rest pivoted on the frame, a second slide-rest pivotally mounted thereon and adjustable at an angle therewith, an arbor journaled on said upper slide-rest at an oblique angle with its longitudinal axis and means for adjusting said rests relatively to 125 each other and to a common plane.

5. In a device of the class described the combination with an adjustable frame, of a

slide-rest pivotally supported thereon, a slide on said rest provided with a cylindric boss thereon, an upper slide-rest journaled on said boss, an upper slide thereon, a frame 5 rigidly engaged on said upper slide, an arbor journaled thereon and a grinding-wheel carried on said arbor.

In testimony whereof I have hereunto subscribed my name in the presence of two subscribing witnesses.

GEORGE ALFRED KIMBER.
